UNITED STATES PATENT OFFICE.

PAUL DIETZ, OF PHILADELPHIA, PENNSYLVANIA, ASSIGNOR TO DEFIANCE MANUFACTURING COMPANY, OF PHILADELPHIA, PENNSYLVANIA, A CORPORATION OF PENNSYLVANIA.

WINDING DEVICE FOR ROLL-FILM CAMERAS.

1,243,270.

Specification of Letters Patent. Patented Oct. 16, 1917.

Application filed November 11, 1915. Serial No. 60,835.

To all whom it may concern:

Be it known that I, PAUL DIETZ, a citizen of the Empire of Germany, and a resident of Philadelphia, county of Philadelphia, 5 State of Pennsylvania, have invented certain new and useful Improvements in Winding Devices for Roll-Film Cameras, of which the following is a specification.

This invention has reference to improvements in roll-film cameras and pertains particularly to a winding device for winding up 10 the exposed film portions.

As usual the film is unwound from one reel and after exposure is wound upon another reel. In order to facilitate the removal of the reel with the film thereon and the insertion of a new reel the winding device comprises the usual key which, in former devices, has to be pulled out and held 15 in that position during the operation of inserting or removing a reel.

The present invention has for its special purpose to produce a winding device for roll-film cameras which is provided with 20 means to keep the gripper mechanism in a permanent position when pulled out until it is released. These same means lock the whole gripper mechanism permanently in 25 the reel and no outward pulling of the key 30 will release any part of said gripper mechanism or loosen the reel, unless intentionally released.

In former devices the key usually is attached to the shaft on which the spring operated device is mounted. In the new winding device the shaft has on its outer end a button or disk and the key is movably attached to a sleeve which is revoluble in one direction only to wind up the film. Only 35 the gripper part which is tensioned by the spring need be moved out when a reel shall be inserted or removed. This is effected by the button or small disk located at the outer end of the shaft. In order to keep the gripper 40 mechanism out of engagement with the reel to easily take out one reel and put in another the winding key is provided with two stop or lock teeth which engage the inner surface of the button or disk, in one instance. Thus the head of said button is 45 kept in a permanent position together with the entire spring operated gripper mechanism thereto attached. The release will be effected as soon as a new reel has been placed

into the camera by simply turning the pivotally mounted key sidewise whereby its locking teeth will be disengaged from the inner surface of the button or disk and the spring operated gripper pin moved automatically back in the usual slots of the reel 55 so that the spring actuated gripper bar permanently locks the reel. If now the key is turned back into an axial plane of the gripper pin then its teeth are located on the outer side of the button which insures the 60 whole spring operated mechanism against any unlocking even if it were attempted to pull out the key or button.

In order to render the invention entirely clear reference is had to the accompanying 70 drawing in which:

Figure 1 represents in face view a roll-film camera partly broken away and embodying in desirable form the present improvement.

Fig. 2 illustrates in side elevation the lower portion of the roll-film camera with the key shown in dotted lines in the turned down position.

Fig. 3 shows on an enlarged scale in longitudinal sectional view the winding mechanism.

Fig. 4 is a detail view of the ratchet and gripper bar mechanism, partly broken away.

Fig. 5 is a perspective view of the gripper bar.

Similar characters of reference denote like parts in all the figures.

In the drawing *a* represents a roll-film camera having sides *b*, *c*. On the inner portion of the side *b* a spring operated reel holding device *d* is provided which is of usual construction. The reel *e* is shown in dotted lines in Fig. 1. On the side *c* of the camera an opening is made in which a sleeve or bearing *f* is mounted which acts inside of the camera as a ratchet hub *f*¹ on which a ratchet wheel *g* is mounted surrounded by a casing *h* which rests against the inner portion of the wall *c* of the camera. The casing has an inner cover *h*¹ and the ratchet is provided with a spring pawl *g*¹ as usual.

Surrounding the sleeve *f* there is a collar and bearing *i* with front cover *i*¹ and a reinforcing frame *j* is mounted upon the inner 105 portion of the collar *i* which frame rests against the side *c* of the camera. Through a central opening in the cover *i*¹ the shaft

k passes which supports the helical spring *l*. On the inner end of the shaft *k* there is the gripper bar arrangement comprising a circular portion *m* and a gripper plate or 5 inner key *n* mounted therein. The gripper plate or inner key has a reduced inner portion *n*¹, *n*², engaging the slots *o*, *o*¹, of the sleeve *f*. Thus the key is engaged and the entire reel may be moved because the inner 10 key or gripper plate *n* is adapted to enter the slot in the film-roll of the reel and thereby lock the reel in position allowing of its rotation.

The shaft *k* of the spring operated gripper mechanism is provided on its outer end with a disk or button *p* by means of which the spring operated gripper mechanism may 15 be pulled out. In order to lock the said mechanism in a permanent position when pulled out the key *q* is of novel construction. The key is pivotally secured to the collar or bearing *i* by means of the screws *r*, *r*¹, so that it may be turned sidewise and rest in a plane parallel to the side wall of 20 the camera casing. The inner body portion of the key is provided with two lock teeth *s*, *s*¹. If now the key is laid so to say flat against the wall of the casing, the button *p* pulled out and the key then moved up in 25 an axial plane of the shaft the stop or lock teeth *s*, *s*¹, rest against the inner surface of the button and hold the same in a permanent position with the entire spring operated mechanism and gripper bar arrangement attached to the gripper shaft on which the button is located. In this manner the gripper mechanism is permanently out of 30 engagement with the reel which then may be taken out and renewed. When a new reel with film has been inserted the key *q* is turned back flat against the wall of the camera casing whereupon the spring forces the gripper mechanism automatically in and 35 the inner key of the gripper bar arrangement lodges in the slot of the reel locking same permanently until released. Now the key is turned back into an axial plane of the gripper shaft but the lock teeth of the key are now located outside of the button and 40

prevent any operation of the same insuring 50 thus said mechanism against any unlocking as long as the key is in the described position.

I claim as my invention:

1. A winding device for roll-film cameras 55 comprising a spool engaging shaft and mechanism for holding the shaft out of engagement with the spool, supporting means for said winding device mounted on one side wall of the camera casing, said holding mechanism comprising a button on the outer end of said shaft and a winding key pivotally mounted on said supporting means and having locking teeth on its inner body portion adapted to engage the inner surface 60 of the button.

2. A winding device for roll-film cameras comprising a spool engaging shaft and mechanism for holding the shaft out of engagement with the spool, supporting means 70 for said winding device mounted on one side wall of the camera casing, said holding mechanism comprising a button on the outer end of said shaft, a flat key with end flanges pivotally secured upon the outer 75 portion of said supporting means and having locking teeth on its inner body portion adapted to engage the inner surface of the button when the shaft has been pulled out.

3. A winding device for roll-film cameras comprising a spool engaging shaft, a button at the outer end of the shaft for pulling out the same, and a key pivotally mounted independent from the button, and having lock teeth on its inner body portion, said 80 key being adapted to be laid flat against the side of the camera casing permitting to pull out the button with mechanism thereon and returned into its initial position so that the teeth engage the inner surface of the button, holding the shaft in the drawn out position until released.

Signed at Philadelphia, Pa., this 9th day of November, 1915.

PAUL DIETZ.
